(57) **CLAIM**

The ornamental design for an electric bicycle, as shown and described.

DESCRIPTION

FIG. 1 is a top, left side perspective view of an electric bicycle showing our new design;

FIG. 2 is a bottom, rear, left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and

FIG. 8 is a bottom plan view thereof; and,

FIG. 9 is an enlarged view of the area "9" shown in FIG. 1. The broken lines depict portions of the electric bicycle that form no part of the claimed design.

1 Claim, 9 Drawing Sheets
